UNITED STATES PATENT OFFICE.

MARCUS M. MOEN, OF CALMAR, IOWA.

ADJUSTABLE DOOR-FRAME.

No. 924,176.

Specification of Letters Patent.

Patented June 8, 1909.

Application filed November 16, 1907. Serial No. 402,470.

To all whom it may concern:

Be it known that I, MARCUS M. MOEN, a citizen of the United States, residing at Calmar, in the county of Winneshiek and State 5 of Iowa, have invented new and useful Improvements in Adjustable Door-Frames, of which the following is a specification.

These improvements relate to adjustable door frames made with an adjustable or 10 movable jamb or rabbet strip, and the objects of these improvements are to provide a method of construction that will make it more convenient to remove the adjustable jamb or rabbet strip from the frame, especially after the frame has been permanently placed; to provide a method of construction 15 by which the adjusting mechanism in the adjustable jamb will be placed and brought into more direct connection with the door 20 hinges or butts and worked out in connection with, or as a part of these butts; and to provide various arrangements and methods of construction for the installation and operation of a transom in a frame with adjustable 25 jambs over the door in adjustable door frames. I attain these objects by new, improved and novel arrangements and methods of construction as hereinafter set forth, and finally as embodied in the claims, and as 30 illustrated in the accompanying drawings in which—

Figure 1 is a sectional view of an upper corner of an adjustable door frame in a vertical plane through the adjusting mechanisms 35 in the adjustable jamb or rabbet strip showing in section a new and improved appliance for joining the adjustable jamb in the sides to the adjustable jamb in the head of the frame, and further showing part of a wall 40 timber and also section of a hinge. Fig. 2 is another sectional view of the upper corner of an adjustable door frame in the same plane as Fig. 1, but showing an appliance heretofore used in adjustable door frames 45 for joining the adjustable jamb in the sides to the adjustable jamb in the head. Fig. 3 is a view of a supporting angle used at the ends of the adjustable jamb in the head of a frame. Fig. 4 is a view of a hook that is 50 inserted into the upper ends of the adjustable jambs in the sides of the frame and engaged and sliding in an opening in the supporting angle described under Fig. 3. Fig. 5 is a front elevation of part of the jambs in an 55 adjustable door frame showing one half of a hinge or butt in place, this butt being made

so as to dispense with the rimmed washer used in connection with the adjusting mechanism in some adjustable door frames, the butt being worked out so as to accommodate 60 the actuating screw with its removable head or nut. Fig. 6 is a sectional view in a vertical plane through the mechanisms in the adjustable jamb of a frame showing a construction that provides for a transom over 65 the door. (In this figure part of a transom and part of a door are shown in elevation as fitted and hung into the frame for the purpose of illustrating this feature of the frame later on in this specification). Fig. 7 is a 70 cross section of a transom bar on the line 11—12 in Fig. 6. Fig. 8 is a cross section of another transom bar that may be used instead of the one shown in Fig. 7. Fig. 9 is a view of a plate bent at one end for insertion into a notch on the rear side of the adjustable jamb on the side of the transom, the other end of which is provided with an 75 opening to receive the hook described under Fig. 4. Fig. 10 is a view of a bracket used 80 in the transom bar shown in Fig. 8, which when fastened to the stationary part of this transom bar is a guiding means for the adjustable jamb in the transom bar, a retaining means for the casing and which has a threaded hole engaging an actuating screw.

In the above described figures of the drawings the same reference letters are used to indicate similar or identical parts.

A is a bracket, B a common washer, C 90 an actuating screw, D a rimmed washer, E a removable screw head or nut, all parts of the adjusting mechanism in an adjustable door frame.

H is a wall timber, I are castings, L is the 95 stationary and N the adjustable jamb in the frame; M is a door, R is a blocking for the stationary jamb, S is a hinge and U a transom.

To arrange for more convenient means of 100 removing the rabbet strip or adjustable jamb N from out of a frame, I employ a supporting angle F³ (see Fig. 3) fastened to the ends of the adjustable jamb N in the head of the frame by a screw O (or screws 105 O). In the opening F⁴ of this support-angle F³ the horizontal extension G⁶ of the hook G³ is slidingly engaged (see Fig. 4). The hook G³ is inserted into the upper end of the adjustable jamb N in the sides of the frame 110 (see Fig. 1) and held in place by a dowel G⁵ inserted into the adjustable jamb in such

a way as to engage a groove G^4 in the hook (see Figs. 1 and 4). The adjustable jambs N in the head and sides of the frame being slid-
5 ingly and operatively joined, as just above described and as the adjustable jamb N in the head is rectilinearly held in place and adjustable by the mechanism in the head of the frame, it follows that the adjustable jamb N in the sides is longitudinally sup-
10 ported and adjustable through the said ad-
justable jamb N in the head.

The adjustable jamb N in the sides may be removed out of the frame after the nut E has been taken off the actuating screw C by
15 simply pulling the horizontal extension G^6 of the hook G^3 out of the opening F^4 in the supporting angle F^3 (see Figs. 1, 3 and 4). Other appliances heretofore employed for
20 the purpose of operatively joining the ad-
justable jambs N in the sides and head at the upper corner of adjustable door frames have not been as convenient for removing the
25 adjustable jambs out of the frame. For instance, the appliance shown in Fig. 2, in which in order to remove the adjustable jamb N in the sides, the said adjustable jamb must first be moved back or pushed into the frame work so as to allow the extended arm F^1 of the supporting bracket F to pass out
30 of the rectangular opening G^1 in the plate G so that the said adjustable jamb may be dropped sufficiently to allow the end of the
35 said plate G to pass under the extended arm of the supporting bracket F . It is very es-
sential that the adjustable jambs in a frame of this kind can be easily and conveniently removed out of the frame for various reasons and purposes, but particularly for the purpose of fastening and securing the edge of
40 casings adjoining the adjustable jamb.

It is essential that the adjustable jamb or rabbet strip be held firmly and rigidly in place especially in the side of the frame to which the door is hung so that the door will
45 swing and work true. To overcome any slight vibration or springiness there might be in the adjustable jamb caused by the weight and operation of the door on the hinges, I provide a hinge in which either
50 an opening is made into which the rimmed washer usually fitted into the face of the adjustable jamb N is inserted, or the hinge itself is constructed or provided with a rimmed washer cup. The adjustable jamb N being rectilinearly held in place by the actuating screw C in the adjusting mechanism, it follows that if the said screw C is brought into direct contact or connection with the door hinge by applying the nut E on the said
55 screw C directly against the hinge as shown in Figs. 1 and 5 the liability to vibration of the said adjustable jamb N on account of the strain on the hinges by the door is entirely eliminated. Further, combining the
60 rimmed washer and the door hinge in a

frame as just above described will in the finished frame present a neater appearance than where these are employed independently and separately.

In adapting an adjustable door frame of
70 this kind for a transom over the door in the frame the general construction and principles remain the same, only variations of the different appliances and mechanisms being necessary.

The plate F^5 (see Fig. 9) is secured to the adjustable jamb N in the sides of the frame above the transom bar by a screw O (or screws O) which is reinforced by the bent end of said plate being inserted into a
80 notch in said adjustable jamb and in this way in connection with the hook G^3 carries the adjustable jamb N in the sides of the frame below the transom bar in the same manner as the combination of the hook G^3 85 and angle F^3 , illustrated in Fig. 1 and previously described.

In Fig. 6 the movable or adjustable part N^1 of the transom bar is inserted between the lower end of the adjustable jamb N at
90 the sides of the transom, and the upper end of the adjustable jamb N at the sides of the door in the frame. The movable or adjustable part N^1 of the transom bar being inserted between the ends of the adjustable
95 jamb N in the sides of the frame in the manner just described, it follows that if the said adjustable jambs N in the sides are raised or lowered by turning the actuating screw
100 C in the head of the frame above the transom that the said movable or adjustable part N^1 in the transom bar will be raised or lowered with the said adjustable jambs N in the sides.

While the casing I (see Fig. 7) is sta-
105 tionary and fastened into the stationary part L^1 of the transom bar by a nail or screw V , the above described movement of N^1 of the transom bar is made possible by the opening P^1 in the said part N^1 through
110 which the said nail or screw V passes.

The combination of the plate F^6 and hook G^3 (see Fig. 6) allows the adjustable jamb N , above and below the transom bar, in the sides of the frame to be rectilinearly ad-
115 justed independently of each other, the horizontal extension of the hook G^3 being slid-
120 ingly engaged in the opening F^4 of the plate F^6 . This is a feature that enables me at all times to have perfect adjustment to the sides of both the transom and the door, no matter what the varying requirements may be in either.

In the frame illustrated in Fig. 6 it will be noticed there is no provision made for
125 increasing or decreasing the height of the opening for the transom; that is, there is no perpendicular adjustment provided for in the frame with reference to the transom alone, the transom bar shown in Fig. 7 being
130

used. If, however, I desire such adjustment I can use the transom bar shown in Fig. 8 in which the movable part of the transom bar is made in two pieces, N^2 and N^3 , the piece N^2 being inserted between the ends of the adjustable jambs N in the sides of the frame in the same manner as the adjustable part N^1 of the transom bar shown in Fig. 7 is in Fig. 6, and perpendicularly moved or adjusted as previously described, while the other piece N^3 is perpendicularly adjustable independently of the said adjustable jambs N in the sides of the frame, by an adjusting mechanism, similar to the adjusting mechanism employed in the sides and head of the frame, except that the bracket A is varied to the shape A^8 (see Fig. 10) to accommodate it for this purpose. The bracket A^8 is fastened to the stationary part L^1 of the transom bar by a screw O (see Fig. 8). The casing I on the transom bar in this instance is fastened and held in position by other screws O in the holes or slots A^7 of the said bracket A^8 .

Having thus described my invention of improvements in adjustable door frames, what I claim is—

1. The combination in the upper corners of adjustable door frames made with an adjustable or movable jamb or rabbet strip, of an appliance consisting of a supporting angle F^3 and a hook G^3 for operatively joining the adjustable jamb in the sides to the

adjustable jamb in the head and for supporting and carrying the said adjustable jamb in the sides by the said adjustable jamb in the head through the adjusting mechanism in the head of the frame, all so arranged that the adjustable jamb in the sides may be removed from or out of the frame by direct movement into the doorway and make more convenient the removal from or out of the frame of the adjustable jambs or rabbet strips, not only in the sides but also in the head, all substantially as and for the purposes set forth. 45

2. The combination in adjustable door frames made with an adjustable or movable jamb or rabbet strip in which the actuating screw in the adjusting mechanism is brought into direct connection with and operated through the hinge butt for the door on the adjustable jamb or rabbet strip, all substantially as and for the purposes set forth. 50

3. The combination with adjustable door frames made with an adjustable or movable jamb or rabbet strip, of a movable and adjustable transom bar, all so arranged that the adjustable jambs or rabbets are independently adjustable to the transom or to 60 the door, all substantially as and for the purposes set forth.

MARCUS M. MOEN.
